(57) **CLAIM**

The ornamental design for a refrigerator, as shown and described.

DESCRIPTION

FIG. 1 is a top-front perspective view of a refrigerator according to our design;

FIG. 2 is a front view thereof, a back view thereof showing no claimed portion of the design;

FIG. 3 is a right side view thereof;

FIG. 4 is a left side view thereof;

FIG. 5 is a top view thereof; and,

FIG. 6 is a bottom view thereof.

Broken lines are environmental only and form no part of the claimed design.

Dash-dot lines adjacent un-shaded areas represent bounds of the claimed design and form no part of the claimed design themselves.

The pairs of closely adjacent, spaced jagged broken lines in the drawings indicate an indeterminate length and form no part of the claimed design.

The diagonal shading using straight lines indicated a highly reflective transparent surface where an evenly applied stipple filled shading with lines is then used to represent a surface immediately under the highly reflective transparent surface.

The stipple fill indicates a dark grey metallic color according to the following CIE Lab color space definition, measured at 25° with an F/2 type illuminant positioned at 10°:

L: 40.56

a: 1.16

b: 7.34.
